DOOR SUPPORTING PULLEY

Alfred C. Farr, Upland, Ind., assignor to Carrie
Horner, Upland, Ind.Application September 29, 1931
Serial No. 565,895

9 Claims. (Cl. 20—16)

This invention relates to brackets and pulleys and is designed particularly with a view to its use in garage doors of the type shown in my recent Patent No. 1,804,329.

5 The object of the invention is to provide means for supporting door operating weights which will be simpler in operation and easier to install than those shown in the patent referred to.

A further object is to provide means for supporting door operating weights which can be 10 adapted to situations in which the pulleys for supporting weights shown in the patent referred to cannot be used.

Further objects and advantages will become 15 apparent as the description proceeds.

Referring to the accompanying drawings which are made a part hereof and on which similar reference characters indicate similar parts,

Figure 1 is a view in elevation of the device 20 showing it applied to a garage door,

Figure 2, a section substantially on line 2—2 of Figure 1,

Figure 3, a section on line 3—3 of Figure 1,

Figure 4, a view in elevation of another form 25 of bracket and pulley,

Figure 5, a section on line 5—5 of Figure 4,

Figure 6, a view in elevation of a combination 30 of brackets, one being that shown in Figure 4 and the other being of a different form,

Figure 7, a section on line 7—7 of Figure 6, and

Figure 8, a view showing the use of a long 35 bracket when placed adjacent the wall of a building.

In the patent above referred to, the door supporting weights are housed in boxes at the side of the door. Under some circumstances it is difficult to arrange the weights and pulleys in the manner shown in the patent because of the lack of room, since it is necessary to have a box sufficiently wide to accommodate the width of the weight with the necessary play to permit free 40 operation. In cases where narrow garages are necessary there is not always room to provide a wide housing or box at the side of the door for the weight. The brackets forming the subject matter of this invention provide for these situations.

In the preferred form of the invention such as that shown in Figure 1 numeral 38 indicates the 45 side post of a garage or other door opening having a piece 39 extending across the top opening of the door. The pulley bracket for supporting a door 60 consists of a vertical member 40 and a horizontal portion 41, each of these portions 50 preferably being formed of angle irons which

may suitably be secured over a corner of the post and cross piece and fastened thereto by bolts or screws 42. Secured to or made integral with the portion 40 is a horizontal bar or bracket portion 43. This bracket portion carries pulleys 44 and 45 on its opposite ends, these pulleys being positioned on opposite sides of the portion 41. A cable 46 passes over each of the pulleys and is attached at one end to a collar 61 on a bracket 47 which is secured to or made integral with a plate 48 secured to the side of the door 60. The outer end of the bracket 47 carries a roller 49 which engages suitable guide tracks 50 on the side of the door post. The cable is preferably secured to the collar 61 in the manner shown in Figure 3. The 55 collar is provided with angular bores 51 and 52 which meet and extend through the periphery of the collar at 53. The cable is positioned in these bores and extends angularly through the collar so as to provide greater friction contact with the 60 sides of the bore. The end of the cable is flared and filled with solder 54 so as to secure the cable firmly in the collar. While I find that soldering the end of the cable is a most efficient and expedient way of securing the cable nevertheless other 65 well known expedients may be employed such as knotting the end of the cable or wedging the end in the bores. To the free end of the cable is attached a weight 55.

In the form shown in Figures 4 and 5 the bracket 70 consists of a short angle portion 10 which fits over the corner of a post 11. The upper end of the angle portion 10 is flat and is set approximately at 45° with the sides of the plates forming the angle as shown at 12 and to the portion 13 is mounted a pulley 13 by means of a bolt or rivet 14. The upper portion of the side 12 turns over at right angles and is formed in the shape of another angle portion 15 which fits under a cross bar 16 above the door. A cable 17 75 passes over the pulley and is attached at one end to the door and to the other end is attached a weight 18.

From the arrangement shown in Figure 5 it will be seen that the space at 19 is too small to accommodate the pulley and the weight 18. By positioning the pulley 13 at a 45° angle to the door it is possible to position the weight 18 in front of the boxing 13 in which position there is room. If the pulley 13 were positioned in a plane 105 parallel to the plane of the door it would be necessary to have a boxing 13 at least the full width of the diameter of the pulley. By the arrangement shown it will be seen that less space is necessary for mounting pulleys and weights 110

of this form than was necessary with that shown in the patent referred to.

When it is desired to mount double doors there is not sufficient room between the doors to house two brackets with their pulleys. The arrangement shown in Figures 6 and 7 provides for this situation. In this form of mounting the bracket shown in Figures 4 and 5 is mounted as shown to support one of the doors, with the weight 20 enclosed in a boxing 21. A bracket is attached to the other side of the boxing 22 and this bracket consists of a horizontal bar 24 attached to a plate 25 which plate is secured to the door jamb. The bar 24 is preferably positioned at an oblique angle with respect to the plate 25 so that it extends away from the edge of the door 26. A supporting leg 27 is pivoted to the under side of the bar at 28 and is hinged to a base 29 which base is secured to the door posts. Pulleys 30 and 31 are pivoted in the bar. The bar preferably consists of two sides which are separated to permit the pulleys to be pivoted between them. The bar 24 may be made up of a single piece or if preferred the two sides may be separate and suitably riveted or bolted together. In the form shown they are made as a single piece. A cable 32 is attached at one end to the door and has a weight 33 suspended to the other end, the cable preferably passing through a slot 34 in the leg 27. As may be seen in Figure 4 the bar 24 extends out well beyond the weight 20 so that the weight 33 may be positioned in a box 35 beyond the weight 20. Both of the weights may be positioned in the space between the edges of the double doors by this arrangement. Figure 8 shows the use of the long bracket against the side wall 36 of a building. Under such circumstances there is not always room enough to accommodate a bracket such as that shown in Figures 4 and 5. As here shown the bar 24 is attached to the cross strip from which the door is suspended. The lower leg 27 rests against the door jamb and the weights are suspended so that they swing over adjacent the wall 36. This provides easy arrangement for supporting the doors where there is not sufficient space to accommodate a housing in which the weights and pulleys may be encased such as is necessary with the arrangement shown in the patent referred to. From the description given it will be seen that the brackets and pulleys of the present invention provide convenient arrangement for balancing and operating the doors when there is not sufficient space to instal the form shown in the patent referred to.

It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

1. A garage door pulley supporting corner bracket comprising a vertical angle iron secured to the doorframe and having its upper end terminating in a flat portion at 45° to the sides of the angle iron, a horizontal angle iron secured to said flat portion and at right angles with the said vertical angle iron and having means for securing it to the cross piece of said frame above the door, a cable supporting pulley mounted in the upper end of said flat portion, a cable, and a weight supported by the said pulley, substantially as set forth.

2. The combination with a pair of weights for counterbalancing a pair of doors of a pair of brackets for supporting said weights relatively close to each other, one of said brackets being shorter than the other, the brackets converging toward each other and carrying pulleys, cables carried by said pulleys, the outer edges of the pulleys lying substantially in a plane at right angles to the plane of the doors being supported, substantially as set forth.

3. Means for supporting a plurality of operating weights for a pair of adjacent vertically opening doors, comprising the combination with the doors of two brackets one having a single pulley with a weight supporting cable thereon attached to one door and the other carrying two pulleys with a weight supporting cable thereon attached to the other door, the brackets converging toward each other away from the edges of their respective doors, substantially as set forth.

4. A garage door pulley supporting corner bracket comprising a vertical angular supporting leg, a horizontal angular supporting portion, and a flat bar attached to said leg adjacent the upper end said bar having a pulley attached to each end, substantially as set forth.

5. A garage door pulley supporting bracket in one piece comprising a vertical supporting leg, a horizontal supporting portion, a bar attached to said leg adjacent the upper end, said bar having a pulley attached to each end and being at an oblique angle to the plane of a face of the said leg, substantially as set forth.

6. Means for supporting the counterbalancing weights of a vertically folding garage door comprising a bracket having a leg for attachment to the door post and a horizontal portion for attachment to a bar above the door opening, said bracket having an angularly disposed bar above said leg carrying pulleys at each end, a cable carried on said pulleys, said cable being attached at one end to the side of the door and at the other end to the door balancing weight, substantially as set forth.

7. Means for supporting the counterbalancing weight of a vertically folding garage door comprising a bracket having angular leg for attachment to the door post and a horizontal angular portion for attachment to a bar above the door opening, said bracket having a bar above said leg carrying pulleys at each end, a cable carried on said pulleys, said cable being attached at one end to the side of the door and at the other end to a door balancing weight, said door having a bracket attached near its edge to which the said cable is attached, said cable passing through angularly arranged openings in the bracket and having its ends flared and filled with solder to effect a secure attachment of the cable to the bracket, substantially as set forth.

8. Means for supporting the counterbalancing weight of a vertically folding garage door comprising a one piece bracket having an angular leg for attachment to the door post and a horizontal angular portion for attachment to a bar above the door opening, said bracket having a bar above said leg carrying pulleys at each end, a cable carried on said pulleys, said cable being attached at one end to the side of the door and at the other end to a door balancing weight, the means for attaching the cable to the door comprising a bracket attached to the door, said bracket having a collar adjacent its outer end, the collar having radial passages at right angles therethrough in which the cable is secured, the

end of the cable being flared and filled with cementing material, substantially as set forth.

9. Means for supporting the counterbalancing weight of a vertically folding garage door comprising a bracket having a leg for attachment to the door post and a horizontal portion for attachment to a bar above the door opening, said bracket having a bar carrying pulleys at each end, a cable carried on said pulleys, said cable being attached at one end to the side of the door, and at the other end to a door balancing weight, the means for attaching the cable to the door

comprising a bracket attached to the door, said bracket having a collar swivelled adjacent its outer end, the collar having radial passages therethrough in which the cable is secured, the end of the cable being flared and filled with cementing material, the end of the bracket having a roller thereon adapted to engage suitable tracks on the door posts to guide the door and hold it in position during vertical movement of the door as it opens, substantially as set forth.
